(57) **CLAIM**

The ornamental design for a laser therapy device, as shown and described.

DESCRIPTION

FIG. 1 is a top left side perspective view of the laser therapy device.

FIG. 2 is a front perspective view thereof;

FIG. 3 is a rear perspective view thereof;

FIG. 4 is a left side elevation view thereof;

FIG. 5 is a right side elevation view thereof;

FIG. 6 is a front elevation view thereof;

FIG. 7 is a rear elevation view thereof;

FIG. 8 is a top plan view thereof; and,

FIG. 9 is a bottom plan view thereof.

The nature and intended use of the article in which the design is embodied is as a therapy device that emits laser energy.
